SHOE COUNTER

Arthur C. Sewall, Auburn, Maine

Application March 2, 1938, Serial No. 193,496

6 Claims. (Cl. 36—68)

My invention relates to shoe counters, and to materials from which said counters may be made.

The invention, which has among its objects the provision of a counter of improved construction, and of improved materials from which the counter may be readily fabricated, will be best understood from the following description when read in the light of the accompanying drawing, the scope of the invention being more particularly pointed out in the appended claims.

In the drawing:

Fig. 1 is a perspective of a counter according to the invention;

Fig. 2 is a longitudinal medial vertical section of the counter according to Fig. 1 with parts broken away;

Fig. 3 is a plan of a blank from which the counter according to Figs. 1 and 2 may be molded;

Fig. 4 is a section on the line 4—4 of Fig. 3 on an enlarged scale;

Fig. 4a is a section of the resilient insert according to Figs. 3 and 4 on a still further enlarged scale;

Fig. 5 is a section corresponding to Fig. 4 showing the counter blank before skiving its edges;

Fig. 6 is a section of a strip from which the counters may be cut;

Fig. 7 is a section on the line 7—7 of Fig. 6;

Fig. 8 is a modified form of strip from which the counters may be cut; and

Fig. 9 is a section on the line 9—9 of Fig. 8.

Referring to the drawing, which illustrates the preferred form of the invention, the counter is provided with a lower side wall portion 1 and an upper side wall portion 3, the lower flange 5 of the counter being formed integrally with the lower side wall portion 1 thereof.

Preferably the portions 1 and 3 of the counter are formed of relatively stiff material such as fiberboard. The upper edge portion of the counter is skived as indicated at 7, and the flange portion 5 as indicated at 9, so that these portions will be relatively flexible and will merge with the adjacent surfaces of the other portions of the shoe. If desired, the portions 1 and 3 need not be of the same material, for example, the portion 1 may be of fiberboard and the portion 3 may be of impregnated bibulous paper or flannel.

As illustrated, the adjacent edges 11 and 13 of the upper and lower side wall portions of the counter are preferably slightly spaced, for example, but without limitation thereto, from $\frac{1}{32}$ to $\frac{1}{4}$ ", and these portions are skived on their outer surfaces as indicated at 15. Uniting the two por-

tions 1 and 3 of the counter is an insert 17 of resilient material, preferably rubber. Conveniently this insert is formed with beveled surfaces 19 corresponding to the skived surfaces 15 of the side wall portions of the counter, and is united to those skived surfaces by cement, preferably rubber cement.

The insert 17 in effect forms a spring hinge resiliently tending to hold the portions 1 and 3 in their normal positions shown in Figs. 1 and 2. It has been, under some circumstances, a defect of counters constructed with a stiff lower portion and a flexible upper portion as, for example, the counter shown by applicant's Patent No. 1,968,572, that when the shoe is worn the upper flexible portion, particularly at the rearward portion of the counter, does not spring back into normal position when pressed inwardly. With the present counter, preferably the body of the portion 3 is stiffer than that portion would be if made of ordinary rubber impregnated bibulous paper or flannel, and to that end preferably is made of fiberboard or other material of equivalent stiffness. By such construction the defects of prior counters are entirely avoided, because the insert 17 forming a resilient hinge tends to return the portion 3 to its normal position when it is pressed inwardly, the resilient effect of the hinge being accentuated at the rearward portions of the counter because the strip forming the insert 17 in the finished counter is bent longitudinally thereof into an approximately U or horseshoe shape as shown by the drawing.

As a convenient way of producing counters having like properties, the blanks therefor may be cut from elongated strips formed according to Figs. 6 and 7. As shown, this strip consists of elongated zones 21 of the material of which the portions 1 of the counters are formed and an elongated zone 23 of the material of which the portions 3 of the counters are formed, these zones consisting of bands of such material. The adjacent edges of the zones 21 and 23 are skived to form the bevels 15 of the counter, and cemented to these bevels are elongated strips 17 of rubber or other resilient material hereinbefore described.

The counters may be cut from these strips, as indicated by the lines 25 in Fig. 6, to form blanks which on the line 7—7 of Fig. 6 have the cross-section indicated by Fig. 5, which blanks are then skived as indicated in Figs. 3 and 4 and are subsequently molded to give the counter the shape shown by Figs. 1 and 2.

According to the modified form of strip shown by Figs. 8 and 9 the central zone 27 of the strip

is formed of a band of the material of the portions 1 of the counters, while at opposite sides of this zone are zones 29 formed of bands of the material of the portions 3 of the counters, adjacent edges of these bands being skived, as indicated at 15, and being united by cementing thereto elongated strips 17 of rubber or the like heretofore described. The counter blanks may be cut from the strip according to Figs. 8 and 9, 10 as indicated by the lines 31 in Fig. 8.

It will be understood that within the scope of the appended claims wide deviations may be made from the embodiments of the invention herein described without departing from the spirit of the 15 invention.

I claim:

1. A shoe counter having a generally U-shaped side wall portion comprising, at at least the bend of said U, a lower longitudinally extending relatively stiff portion, an upper longitudinally extending relatively flexible, relatively non-resilient portion, and a longitudinally extending resilient insert connecting the upper edge portion of said lower wall portion to the lower edge portion of 25 said upper wall portion.

2. A shoe counter having a generally U-shaped side wall portion comprising, at at least the bend of said U, a lower longitudinally extending relatively stiff portion, an upper longitudinally extending relatively flexible, relatively non-resilient portion, and a longitudinally extending band of 30 resilient material united by overlapping joints with the lower edge portion of said upper wall

portion and the upper edge portion of said lower wall portion.

3. A shoe counter having a generally U-shaped side wall portion comprising upper and lower bands extending from one end to the other of 5 said wall, the upper edge of said upper band being beveled to approximately a feather edge and being relatively non-resilient and the lower band being relatively stiff, and a band of relatively resilient material extending from one end 10 to the other of said wall united by beveled overlapping joints to the adjacent edges of said upper and lower bands.

4. A counter according to claim 3 in which 15 said upper and lower bands are of fiberboard and the band of resilient material is rubber.

5. A shoe counter having a generally U-shaped side wall portion comprising a longitudinally extending relatively narrow upper band extending from one end to the other of said wall and having 20 widely beveled upper and lower edges, the upper edge being relatively non-resilient, and a lower relatively wide, relatively stiff band extending from one end to the other of said wall and having a widely beveled upper edge, the adjacent 25 edges of which bands are slightly spaced; and a band of resilient material having upper and lower beveled edges complementary to said beveled edges of said bands and cemented thereto.

6. A counter according to claim 5 in which said 30 upper and lower bands are of fiberboard and the band of resilient material is rubber.

ARTHUR C. SEWALL.
